[57] CLAIM

The ornamental design for a portable warning light, as
shown and described.

DESCRIPTION

FIG. 1 is a front perspective view of a portable warning
light showing my new design;

FIG. 2 is a side elevational view thereof;

FIG. 3 is a rear elevational view thereof;

FIG. 4 is a bottom plan view thereof on an enlarged
scale; and

FIG. 5 is a top plan view thereof on an enlarged scale.
The standard is broken away in FIGS. 1, 2 and 3 to
indicate indeterminate length.

FIG. 1

FIG. 2

FIG. 3

FIG. 4

FIG. 5
